UNITED STATES PATENT OFFICE.

EDWARD G. SCHRIEFER, OF CINCINNATI, OHIO.

EXTENSIBLE CASE.

No. 909,951.

Specification of Letters Patent.

Patented Jan. 19, 1909.

Application filed January 26, 1903. Serial No. 140,592.

To all whom it may concern:

Be it known that I, EDWARD G. SCHRIEFER, a citizen of the United States, residing at Cincinnati, in the county of Hamilton and State of Ohio, have invented certain new and useful Improvements in Extensible Cases, of which the following is a specification.

My invention relates to improvements upon the extensible cases shown, described and claimed in my applications for Letters Patent of the United States, Serial Nos. 92460, 92461, 92462 and 92463, all filed February 3, 1902, for extensible cases, and my invention consists in new and improved construction of door and means for forming a composite door out of several doors of superposed sections; in new and improved means of constructing the base and top of an extensible case for providing clearance at top and bottom for the door to swing, in new and improved means for holding the door in closed relation and locking the same in that position; in new and improved means for 25 positioning a shelf with relation to the doors; in new and improved means between sections for compensating for shrinkage or expansion of material, and providing for proper relative swinging of the doors; in new and improved means for connecting superposed sections; and in the parts, and in the construction, arrangement and combinations of parts hereinafter more fully described and claimed.

35 In the drawings: Figure 1 is a perspective view of my improved device showing one door swung open and partly exposing the interior of the case, and partly broken away to show details of construction. Fig. 2 is an 40 enlarged vertical cross section of my improved device, taken on a line corresponding to the line $w-w$ of Fig. 1, partly broken away, showing the means for connecting superposed door-sections, and for providing 45 clearance at top and bottom of the combined door, and means for compensating between sections for shrinkage or variation of material. Fig. 3 is a perspective view partly broken away showing the connection between 50 superposed case-sections and between superposed door-sections. Fig. 4 is a front inside elevation showing the connecting means between superposed door-sections of my improved device, with the door-sections partly 55 broken away. Fig. 5 is a plan view of the same. Fig. 6 is a longitudinal section taken

on the line $z-z$ of Fig. 7 showing the pull and lock in connection with the door stile. Fig. 7 is a front elevation of the same. Fig. 8 is a detail showing the relation of the top board and side of the base-section, and showing the side catch between the base-section and a case-section in side elevation, with said top board in cross-section on the line $y-y$ of Fig. 10. Fig. 9 is a detail of the same in section on a line corresponding to the line $w-w$ of Fig. 8. Fig. 10 is a plan view of the same. Fig. 11 is a detail in front elevation showing one end of the top-section and a case-section, partly broken away, to 70 show the manner of constructing the same and the relation of the parts to each other. Fig. 12 is a bottom view, partly broken away, showing adjoining ends of adjoining case-sections, and showing the manner of hinging 75 the doors, and my improved pull for opening the doors, the pull permitting the outer ends of the doors to be moved past each other in opening without permitting catching of the doors one on the other, the means for holding 80 the doors in closed relation and locking the same in that relation, and means for positioning the shelf with relation to the door. Fig. 13 is a view in perspective partly broken 85 away showing the manner of constructing the base for receiving a case-section and the clearance for the bottom of the door. Fig. 14 is a view in perspective of the spring catch for holding the door closed. Fig. 15 is a perspective view of the protecting hook 90 taking over the catch. Fig. 16 is a detail partly broken and in end elevation showing the locking plate connection with its door stile. Fig. 17 is a front inside elevation of the same. Fig. 18 is a detail showing the 95 hinge in spread relation connected to a side and door. Fig. 19 is a detail in cross-section on the line $v-v$ of Fig. 12 showing the manner of hanging and positioning the shelf.

A represents the top-section of my improved device, B B' B² the case-sections, and C the base-section. The top-section consists preferably of sides 1 2, a top 3, back 4, and front 5. (See Figs. 1, 2 and 11.) The inside front edges of the sides 1 and 2 are 105 provided with rabbets 6 for receiving the front 5 leaving the reduced projections 7, 8 of the sides show at the front of the top-section in the form of a molding of a width to correspond with the width of the exposed 110 reduced projections of the sides of the case-sections hereinafter described. The lower

edge 9 of the front 5 is in a plane above the lower edges 10 of the sides so that a clearance 151 is provided at the top of doors of case-sections when the sections are superposed, in 5 manner hereinafter explained. This clearance and the rabbet 6 also permits the hinged inner side edge of the door to project into the horizontal plane of the top-section if the combined height of superposed doors should 10 be greater than the combined height of superposed sides of case-sections. The case-sections comprise preferably the sides 11 12, back 13, and doors 14 15. The base-section comprises preferably the sides 16 17, top 15 board 18, back 19, and front 20.

One end of each side of the case-sections, preferably the upper end, has a tongue 21 and the other end thereof, preferably the bottom, has a groove 22 extending short of 20 the front edges of the sides, the tongue being preferably a separate strip secured in the groove 23, with the groove 22 of substantially greater width than the tongue for allowing clearance between the tongue and 25 side walls of the groove for permitting ready seating of the sections one on the other and allowing for shrinkage and variation. (See Figs. 1, 2, 3 and 12). The bottom edges of the sides 1 and 2 of the top-section also have 30 grooves 22. Near its front edge each side of the case-sections is provided with a dowel 24, preferably in its top, while preferably its bottom has a dowel-hole 25, the dowel and dowel-hole having a close fit for positioning 35 superposed sections at their front edges. The base-section also has a dowel 24 at each side and the top-section a dowel-hole 25 at each side in the vertical plane of the dowels and dowel-hole of the case-sections so that 40 any of the sections may be placed one above another with the front edges registering, making the sections interchangeable. The tongue preferably meets the dowel and the groove 22 preferably merges into the dowel-hole. 45 The backs of superposed case-sections have, at their top and bottoms respectively, or vice versa, a tongue 26 and a groove 27, the groove being of substantially greater width than the tongue. The bottom of the back- 50 board 4 of the top-section also has a groove 27. The object of providing these grooves of substantially greater width than the tongues is to allow for shrinkage or expansion of material as will be hereinafter explained.

At the front of the sides of the case-sections rabbets 28 29 are provided, leaving front projections 30 31, in the form of a molding, of a width preferably of the front 60 projections 7 8, of the top-section. (Figs. 1, 3, 11 and 12). The inner side walls 32 of said front projection of the top-section and the inner side wall 33 of said front projection of the case-section are shown in a 65 vertical plane one above the other. (See

Fig. 11). The doors of the case-sections swing on hinges 34 in upright positions, the hinges being secured to the doors and the sides, the vertical planes of the hinges being near the vertical planes of the dowels at the 70 respective sides. The hinges are preferably loose-pin butt hinges (see Fig. 18) comprising the butts 35 36, secured respectively to the side and door, and loose pin 37 taking through the knuckles 38 of the butt 35 and 75 the knuckles 39 of the butt 36, the lower edges 40 of the knuckles 39 resting on the upper edges 41 of the knuckles 38, so as to position the lower edges of the doors flush with the lower edges of the case-sections, 80 and having the clearance 42 between the upper edges 43 of the knuckles 39 and the lower edges 44 of the knuckles 38 for permitting the door-sections to accommodate themselves vertically upon the pins of the hinges should 85 the combined superposed door be of greater height than the combined height of superposed sections, the extra height of door finding accommodation in the clearance 151, the construction being such also that accidental 90 lifting of the door off its hinges is prevented. The door-sections at their hinged edges are also provided with outer rabbets 45 for permitting the doors to swing open a greater distance. (See Figs. 3 and 12). The rabbets 28 29 form recesses into which the edges of the doors may swing, the inner corners of the rabbets forming shoulders 46 (Figs. 12 and 18) against which the inner edge of 95 one butt of the hinge may take, the inner edge of the other butt of the hinge being flush with the inner face 47 of the door. The hinges are let into recesses 48 in the hinged edge of the door. The recesses are sufficiently deep to accommodate both butts 100 of the hinges. This construction of door-hanging insures ease and accuracy in hanging the doors so that superposed doors may have their hinges accurately one above the other. 105

Respectively the top and bottom of the door are provided with an inside rabbet 49 and an outside rabbet 50, or vice versa, (Figs. 2, 3, 4, 5 and 12) so as to provide adjoining side faces 51 52 and top and bottom meeting faces 53 54, and inner and outer reduced projections 55 56 for superposed doors when arranged in superposed positions. 110

In order to connect superposed sections 120 of doors I provide a door catch D (Figs. 1, 2, 4 and 5) comprising a swingable lever 57 pivoted on a rivet 58 to a plate 59 secured to one door-section and having a flat shank 60 taking under a lip 61 struck up from a plate 62 secured to the meeting end of the door-section above. The lip is resilient and the shank is snugly held and yieldingly pressed between the lip and plate. The edge of the lip is provided with a series of preferably 125 130

concentric contact faces 63 eccentrically arranged with relation to the pivot of the lever. The outer end of the lever has a lug 64 at its side struck outwardly for forming 5 a flat grip for the lever extending longitudinally of the lever. A shoulder 63 on the lever takes against said contact faces, which, being consecutively arranged farther from the pivot of the lever, draw the sections of 10 doors toward each other. The shoulder is adapted to rest in seats 67. The top face 53 and the lower face 54 of superposed door-sections are thereby clamped together, the lever spanning the meeting faces of the door-sections and preventing relative sidewise movement of the door-sections, the reduced projection 55 of one door-section being rigidly held between reduced projection 56 of the other door-section and the lever, as 15 shown in Fig. 2. The door-sections are thereby clamped vertically and laterally for forming a rigid united door. In practice this construction of the door-sections and their connections practically form a solid 20 door.

Wood, which is subject to shrinkage and variations in dimensions from time to time, is a material out of which my improved extensible case may be made, and my improved 25 construction is such that these variations will not detrimentally affect the operation or construction of the parts, provision being made for accommodating such changes. The dowels, being near the front edges of the 30 sections, position those front edges irrespective of what sections are superposed so as to assure the pintles of the hinges of superposed case-sections to be one above the other, and there being such little material between 35 the dowels and hinges, there is substantially, in practice, no variation in relative position between the dowels and hinge-positions. The grain of the wood of the sides of case-sections usually runs lengthwise of those sides. 40 The dowels form the fixed points from which shrinkage and variation take place, and the relatively wider grooves at the sides and back permit shrinkage and variation of the major part of the case while the tongues in 45 the grooves act as dust-strips. The clearance 151 and the clearance between the butts of the hinges also permit the door-sections to be made slightly higher than the sides of case-sections, if desired, while the 50 projections 55 56 act as dust-strips with sufficient lap for allowance for shrinkage or variation, the said clearance also permitting the door to project into it in case of 55 swelling of the door.

60 In order to provide for proper lapping of the doors at the middle when the case is closed I provide one of the doors with an outside rabbet 71 and the other door with an inside rabbet 72 for forming lips 73 74 be-

tween the doors. (See Fig. 12.) In my 65 improved construction therefore the doors have an inner reduced projection at one vertical end and an outer reduced projection at the other vertical end, while the right-hand door has an inner reduced projection at one 70 side and an outer reduced projection at its other side, the left-hand door having an inner reduced projection at both sides. (See Figs. 2, 3 and 12).

In order to insure closing of the doors at 75 various positions at which a shelf may be placed vertically of the door I provide the door with a rod 75 secured thereto by screws 76 taking through apertures in the rod and ferrules 77 and screwing into the door-stile, 80 the rod extending up and down lengthwise of the door-stile. The mating doors of a given case-section of a case may each be provided with a rod of this kind while the doors of the remaining case-sections may be free 85 of this rod, the one pair of rods with their springs and catches to be presently described being sufficient to hold closed the composite door when the various sections of the door are connected. (See Figs. 1 and 12.) A 90 spring-catch F comprises a spring-plate 78 having suitable spring fingers 79 80 projecting therefrom for receiving the rods when the doors are closed. A hood 81 takes over the spring fingers for protecting the same and preventing injury therefrom, the hood 95 being provided with transverse slots 82 into which the rods may pass into engagement with the spring fingers, the corners and edges of the hood being rounded. Spring 100 fingers with their plate and hood are suitably secured to the shelf as by means of screws 83. The screw 83 passes through a hole 84 in the hood and a hole 85 in the spring plate. The shelf also carries a hook 105 86 pivoted preferably at its bottom as on a screw 87, and is adapted to take about one of the rods for holding one of the doors closed against outward pull. The other door is provided with a lock 88, the bolt 89 of 110 which is adapted to take in rear of a plate 90 in an undercut channel 91 at the bottom of a recess 92 in lip 73, a screw 93 taking through a slot 94 in plate 90 into the lip for 115 adjustably positioning the plate 90 with relation to the edge of the lip so as to project a greater or less distance beyond the lip for receiving the bolt in case of variations in distance between doors. (See Figs. 12, 16 and 17). The spring-fingers and hood and hook 120 are carried with the shelf as the latter is raised and lowered in the case and are adapted to act on the rod throughout various elevations of the shelf so that the door may be 125 releasably closed throughout the various elevations and also locked throughout those elevations. The plate 78 has an upwardly pressed part 95 upon which the spring-fin-

gers are secured for raising the yokes 96 of the spring fingers into vertical line with the inner walls 97 of the apertures 82.

E represents the shelves for supporting which I provide means similar to the shelf supports shown, described and claimed in my application Serial No. 105388, filed April 30, 1902, for adjustable shelf supports, upon which my present construction is an improvement in extensible cases. I provide shelf strips 101 102 at front and rear of each side of the case-sections sunk into said sides, and having openings 103 into which hooks 104 of shelf-supports 105 take for hanging the shelf-supports on the strips. The shelf-support at its front end has an upwardly projecting outwardly inclined lip 106 having a front contact face 107 and a rear contact face 108. The bottom of the shelf at each end at its front portion is provided with a slot 109 over which a plate 110 provided with a slot 111 shorter than the latter slot is adapted to be secured, as by screws 112, 113 taking through slots 114 115 in the plate 110 and into the shelf. The slot 111 has a front wall 116 and a rear wall 117 for contacting with the faces 107 108. Movement of the hook 104 in the opening 103 is limited by the side edges of the hook contacting with the ends of the opening. The plate and lip position the front of the shelf with relation to the front of the case-section for determining the position of the spring-fingers, so that those fingers may be accurately placed for receiving the rods of the doors and holding the doors closed in proper position. The rear of the shelf stops short of the rear of the case-section, leaving a clearance 118 for permitting the rear of the shelf to freely position itself according to the shrinkage of the wood that may take place. The shelf-support is also preferably provided only at its front end with a lip 106, the rear of the shelf-support preferably being without the lip, with the rear of the shelf resting on the ledge 119 of the shelf-support.

In order to permit the outer edges of the doors to swing past each other freely when the cases are arranged in lateral extension and at the same time provide convenient means for opening the doors I have provided a door of each case-section with a pull 121 having a bulged portion 122 and shank 123 through which shank screws 124 pass into the door stile for securing the pull to the door. (See Figs. 6, 7 and 12). The door stile is also provided with a recess 125 projecting under the pull and past the bottom of the pull, for greater freedom in admitting the finger under the pull. The bulged portion of the pull has the sloping sides 126 127, meeting the door stile and permitting the stile of the door of the adjoining section to slide upon the outer surface of the

pull without danger of injury of projecting points. The shank is provided with horns 128 129 forming a rounded upper end 130 taking snugly about the rounded outer end of the tube 131 of lock 88.

For further securing the sections together when arranged in vertical extension I provide the improved side catch G (see Figs. 8, 9 and 10) comprising the lever 132 pivoted on a rivet 133 on a plate 134 secured to one section, the lever lapping the next section and taking under a lip 135 struck up from the plate 136, the lever being snugly held between the lip and plate and yieldingly pressed therebetween, the lip having resilient properties. These side catches are secured and operated within the planes of extension of the sides, being located in recesses 137 138 respectively at the top and bottom of the sides of sections. The lip 135 is provided with a series of contact-faces 139 eccentrically arranged with relation to the pivot of the lever, the lever having a lug 140 at its side struck outwardly for forming a flat engaging surface for operating the lever; a contact face 141 on the lever engaging the faces on the lip for drawing superposed sides toward each other and keeping them in drawn relation from the inside of the case, the lever spanning superposed sections.

A lug 142 is provided for limiting retraction of the lever in such position that the lever, when retracted, may rest practically flush with or below the edge of the section to which it is secured or the upper edge of the plate 134. The contact face 141 is adapted to rest in seats 155 in the lip 135. Similar catches also connect the top-section and a case-section to the base-section. The top board 18 of the base is provided with a slot 143 through which the lever 132 projects, and in which the plate 134 lies, the plate being secured below the top board by the nails 144 to the inside of the sides 16 17 in recesses 137 in those sides. (See also Fig. 13).

The top face of the top board 18 has its side edges provided with recesses 145 inside the side rabbets for admitting the finger or thumb for raising the lever. The top board of the base-section is provided with side rabbets 146 147 and a rear rabbet 148, the lower faces of which are of substantially similar elevation, the front of the base being provided with a deeper rabbet 149. (See also Fig. 2). The base is also provided with dowels which are located in said rabbets 146 147, and the lowest case-section is adapted to rest on the lower faces of the rabbets at the side and rear of the base-section, the rear rabbet being sufficiently wide to allow a clearance 150 to accommodate shrinkage or variations of material. As already explained clearance 151 is provided

in the top-section for the door. The deeper rabbet 149 provides clearance in the base-section, as shown at 152, for the bottom of the door. The clearances in the top and base sections for the top and bottom of the doors accommodate variations in height or sagging of door-sections or the united door and permit ready closing and opening of the door without binding. The upper reduced projection 56 of the door takes against the front face 153 of the top-section and the lower reduced projection 55 of the lowest door takes against the front face 154 at the base-section. Overlapping is thus provided between the doors and inside of the case at top, bottom and sides for arresting dust irrespective of the height of the combined doors. It will also be noticed that the front face 153 is projected forwardly a distance corresponding to the width of the rabbet in the top of the top-section of the door so that the front faces 153 154 are in different vertical planes.

Having thus fully described my invention what I claim as new and desire to secure by Letters Patent is:

1. In an extensible case, the combination of case-sections open-ended at top and bottom, a door for each of said sections, said doors hinged for swinging in upright positions, and a top section, said case-sections arranged to be interchangeably placed as units under said top-section, the lower edge of the front of the top section being above the lower edges of the sides of the same for affording clearance in said top-section for said door of any selective case-section placed immediately under said top-section, said front forming a stop in said top-section against which said door of any so selected case-section strikes for limiting inward movement of said door.

2. In an extensible case, the combination of case-sections open-ended at top and bottom arranged to be interchangeably placed one above another for forming a continuous interior, door-sections of substantially the height of a case-section for each of the said case-sections hinged to the respective case-sections for swinging in upright positions, a base-section, said case-sections arranged to be interchangeably superposed immediately upon said base-section, and means for connecting the door-sections, for forming a united door, said base-section having a front face acting as a stop for said united door, said base-section provided with means for supporting a case-section with the lower edge of said case-section extending below the upper edge of said front face and the lower edge of said front face extending substantially below the lower edge of said case-section for providing substantial clearance for said door while swinging on an upright axis.

3. In a system for extensible cases, the combination with case-sections open-ended at top and bottom and arranged to be interchangeably superposed for forming a continuous interior, each of said case-sections comprising sides and a door-section, said door-sections mounted for swinging in upright positions, means for connecting superposed door-sections for forming a united door, a top-section and a base-section, said case-sections with the door-sections thereon arranged to be selectively interchanged as units immediately next said respective top-section and base-section, said top and base-sections each having a front face forming a stop for the united door irrespective of said selective superposing of its component door-sections with said case-sections as units, within the horizontal plane and extending up and down substantially beyond the horizontal plane of said united door of said case-sections for forming clearance at top and bottom of said united door.

4. In a system for extensible cases, the combination of case-sections open-ended at top and bottom, each of said case-sections comprising sides and door-sections, hinges between the door-sections and the sides of each case-section, a rabbet at the top and a rabbet at the bottom of each door-section for forming rigid projections at the horizontal ends of said door-sections arranged to overlap when superposed, means for connecting superposed door-sections for forming a united door, a top-section, an outer stop therein for the united door, a base-section, and an outer stop therein for the united door, said stops permitting said united door to swing outwardly in upright position, with one of said stops in advance of the other.

5. In combination, in an extensible case, superposed door-sections swinging on an upright axis and having alternate inner and outer vertical extensions forming lapping joints between immediately superposed door-sections, and connecting means at said lapping joints for forming a united door, said connecting means comprising a lever pivoted to one door-section and a lug with which the lever engages secured to the other door-section, with one of said vertical extensions taking between the other of said vertical extensions and said lever when said door-sections are connected, said extensible case comprising a top-section, a base-section, and case-sections open-ended at top and bottom arranged to be interchanged between said top-section and base-section.

6. In an extensible case, the combination of case-sections, each of said case-sections comprising a pair of sides, each side having a rabbet at its inner front edge and a shoulder 46 in said rabbet, a door-section for each side in said rabbet, hinges therefor, said

shoulder guiding the butts of said hinges in securing the hinges to the side, each door-section having an outer rabbet at its hinged side adjacent to the side.

- 5 7. In an extensible case, the combination of a case-section comprising sides and a door hinged in upright position to a side, said door having an inner rabbet at one horizontal end and an outer rabbet at its other 10 horizontal end and an inner rabbet at one vertical side and an outer rabbet at its other vertical side, substantially as described.

8. The combination, in an extensible case, of a top-section, a base-section and case-sections, doors for said case-sections each having an inner rabbet and an outer rabbet at its respective horizontal ends forming projections extending up and down between superposed sections of a united door, and 15 means for connecting said sections and thereby forming a united door, said door swinging on upright axis, and said base-section and top-section each having an outer face respectively extending up and down against 20 which said door projections take.

9. The combination, in an extensible case, of a top-section, a base-section and case-sections, doors for said case-sections each having an inner rabbet and an outer rabbet at 30 its respective horizontal ends forming projections extending up and down between superposed sections of a united door, and means for connecting said sections and thereby forming a united door, said door swinging on upright axis, and said base-section and top-section each having an outer face respectively extending up and down against 35 which said door projections take, said outer faces being in different vertical planes.

40 10. In an extensible case, the combination with a top-section, a base-section and a series of case-sections, each of said case-sections comprising sides, the inner front edges of said sides having rabbets, a door-section 45 hinged on upright axis to each side at the rabbet, said door-sections each having an outer rabbet at its hinged side and an inner and an outer rabbet at its horizontal ends for forming lapping projections for immediately superposed door-sections at said 50 ends, and means at said lapping ends for connecting said door-sections for forming a united door, the inner sides of door-sections having side projections for lapping 55 mating door-sections, the top section and the base-section each having an outer front face against which the door takes from the outside of the case for forming a lap between the door and the top and base-sections respectively.

60 11. In combination in an extensible case, a top-section comprising sides 1, 2 and a front 5, each of said sides having a rabbet 6 at its inside front edge for receiving the

ends of the front, said sides each having a 65 lower edge 10 and said front having a lower edge 9 longitudinally in horizontal plane above said lower edges of the sides, said lower edge of said front having a front face 153, a case-section and a door therefor 70 hinged for swinging in upright positions, said door having a top edge taking under said lower edge of said front and an upward projection taking against said front face.

12. In an extensible case, the combination 75 with a case-section and a door-section swinging thereon at its front on upright axis, the bottoms of the case-section and door-section being in the same horizontal plane, of a base-section provided with side rabbets 146 80 147 at its side ends forming supports for the sides of said case-section, and a front rabbet 149 having a rear wall and merging with said side rabbets and extending below the bottoms of the latter and forming a stop for 85 said door-section and clearance below the bottom of said door-section within the horizontal plane of said base section, substantially as described.

13. In combination, in an extensible case, 90 superposed door-sections swinging on a vertical axis and having alternate inner and outer vertical extensions for forming lapping joints between superposed door-sections, connecting means at said lapping 95 joints for forming a united door, a top-section, and a base-section, said top-section and said base-section each having a front striking face for said door, said striking faces being in different vertical planes, substantially 100 as described.

14. In combination, in an extensible case, superposed door-sections swinging on a vertical axis and having respectively an outer vertical extension and inner rabbet at one of 105 its horizontal ends, and an inner vertical extension and outer rabbet at the other of its horizontal ends, superposed case-sections, said door-sections hinged to the sides of the case-sections, each of said doors and one of said 110 extensions being the exact height of the side to which it is hinged, adjacent extensions resting in adjacent rabbets when said door-sections are superposed, and connecting means between superposed door-sections for 115 forming a unitary door, substantially as described.

15. In an extensible case, the combination of interchangeable case-sections, door-sections hinged thereto, said case-sections with 120 their door-sections adapted to be interchangeably placed as units one above the other, and a clamp for connecting the door-sections when so arranged for forming a united door, said clamp comprising a connecting link pivoted to one door-section, the other door-section having a shoulder with which said pivoted connecting link engages,

said pivoted connecting link spanning the space between said door-sections and arranged to draw said door-sections one toward the other.

5 16. In an extensible case, the combination of a base-section and a case-section, the base-section having rabbets at its sides and back, said case-section and base-section having a dowel and dowel-hole connection between 10 the same located solely adjacent to the front edge of the case-section in said side rabbets for definitely relatively positioning said case-section and base-section only at the front edges thereof and permitting variations in position relatively between the rear of the case-section and base-section.

15 17. In an extensible case, the combination of a base-section having a rabbet at each side and at the back and a case-section comprising sides and a back, with said back of 20 said case-section of less thickness than the width of said back rabbet in said base-section for affording clearance between the front wall of said back rabbet and the back 25 of the case-section, the base-section and case-section having a dowel and dowel-hole connection between the same adjacent to the front edge of the case-section for relatively definitely positioning said case-section and 30 base-section at the front only.

35 18. In a system for extensible cases, the combination of case-sections open-ended at their tops and bottoms and each comprising a back and a pair of sides, and means in each 40 for supporting a shelf at various elevations, one horizontal end of each having a dowel adjacent to its front edge and the other horizontal end of each side having a dowel-hole adjacent to said front edge, with the case- 45 sections arranged to be placed interchangeably one on another and when so placed having dowel and dowel-hole connections in the same vertical plane between all case-sections at each side solely adjacent to said front edge and with horizontally shifting connection throughout the balance of adjacent ends of said superposed case-sections, said adjacent ends having overlapping parts in rear of said dowels and dowel holes when 50 so superposed, and forming a united case having a continuous interior open-ended at top and bottom.

55 19. In an extensible case, the combination of case-sections arranged to be superposed, door-sections of substantially the height of 60 said case-sections swinging in upright positions, hinges connecting said door-sections with said case-sections, each of said case-sections comprising a pair of sides and a back, said sides each having a dowel and dowel-hole at its horizontal ends solely adjacent in vertical plane to the hinges of the door-sections and having lapping extensions between immediately superposed case-sections with

horizontal shiftable connection to the rear 65 of said dowel and dowel holes for permitting case-sections with their door-sections to be interchangeably placed one on top of another with said dowel and dowel-hole connections in similar vertical plane between all 70 case-sections at each side of said case-sections and with said hinges and door-sections positioned respectively in similar vertical planes.

75 20. In an extensible case, the combination of case-sections, door-sections of substantially the height of said case-sections swinging in upright positions, hinges between the door-sections and case-sections, each of said case-sections comprising a pair of sides and 80 a back, said sides each having a dowel and dowel-hole at its horizontal ends adjacent in vertical plane to the hinges of the door-sections for permitting case-sections with their door-sections to be interchangeably placed 85 one on top of another with said dowel and dowel-hole connections in similar vertical plane between all case-sections at each side of said case-sections, said hinges and door-sections positioned respectively in similar 90 vertical planes, said sides each also having a tongue and groove at its horizontal ends in rear of said dowel and dowel-hole, said groove being of substantially greater width than the tongue for accommodating shrinkage and variation. 95

100 21. In an extensible case, the combination of case-sections, door-sections of substantially the height of said case-sections swinging in upright positions, hinges between the door-sections and case-sections, each of said case-sections comprising a pair of sides and a back, said sides each having a dowel and dowel-hole at its horizontal ends adjacent in vertical plane to the hinges of the door-sections for permitting case-sections with their door-sections to be interchangeably placed one on top of another with said dowel and dowel-hole connections in similar 105 vertical plane between all case-sections at each side of said case-sections and with said hinges and door-sections positioned respectively in substantially similar vertical planes, said back having a tongue and recess at its horizontal ends, said recess being of substantially greater width than the tongue for 110 accommodating shrinkage or variation in case-sections.

115 22. In an extensible case, the combination of case-sections having sides and a back arranged to be superposed and doors hinged thereto on vertical axes, and dowel and dowel-hole connections at the front edges of said sides arranged in similar vertical planes when said case-sections are superposed, said 120 case-sections having lapping parts and space between said parts for forming laterally shifting connection at adjacent ends in rear 125

of said dowel and dowel-hole connections, substantially for the purpose specified.

23. In an extensible case, the combination with a case-section open-ended at top and bottom, a shelf and means for adjustably positioning the same to height in said case-section, a door swinging in upright position on the case-section, door-securing means supported by the shelf and moving with it in its adjustments, engaging means for the latter extending up and down on the door for engaging said door-securing means at various shelf elevations, and a protecting hood taking over the means on the shelf, substantially as described.

24. In an extensible case, the combination of a case-section having doors swinging in upright positions, a rod secured in upright position to a door, a shelf and means for adjusting the shelf at various elevations in the case-section, a spring finger engaging the rod for releasably holding the door closed against outward pull, a protecting hood taking about the spring-finger and having an aperture into which said rod takes and a hook secured to the shelf taking about said rod, said spring-finger, hood and hook secured to and moving with the shelf into various shelf elevations.

25. In an extensible case, the combination of a case-section, a pair of doors hinged thereto and swinging in upright positions, a rod secured in upright position to a door, a shelf, means for adjusting the shelf to various elevations in said case-section, a hook pivoted to said shelf and taking about said rod at various shelf-elevations, and a lock secured to the other door for locking said doors, said hook secured to and moving with said shelf into its various elevations.

26. In an extensible case, the combination of a case-section, a pair of doors hinged thereto and swinging in upright positions, a rod secured in upright position to one of said doors, a shelf, means for supporting said shelf at various elevations in said case-section, a hook pivoted to said shelf and moving with it to its various elevations and taking about said rod at its various elevations, a lock secured to the other door, said lock having a bolt, a bolt-plate and means adjustably securing said bolt-plate to said first-named door whereby said bolt-plate is permitted to selectively project beyond the inner edge of said door for receiving the bolt.

27. In an extensible case, the combination of a case-section having doors swinging in upright positions, a rod secured in upright position to one of said doors, a shelf, means for adjusting the shelf at various elevations in the case-section, a spring-finger engaging the rod for releasably holding the door closed against outward pull, a protecting

hood taking about the spring-finger and having an aperture into which said rod takes, a hook secured to the shelf taking about said rod, said spring-finger, hood and hook secured to and moving with the shelf into various shelf-elevations, a lock secured to one of said doors, a retaining plate on the other of said doors for the bolt of the lock and means for adjustably positioning said plate on its door for projecting a greater or less distance beyond the side of said door.

28. In an extensible case, the combination of a case-section having sides and a door hinged thereto on upright axis, a shelf, door-securing means on said shelf, co-acting means therefor extending up and down on said door, means between the shelf and sides for supporting the shelf at various elevations with relation to the sides, means for limiting movement between said latter means and the sides toward and from the front of said case-section, a slidable plate 110 having an elongated slot 111 extending lengthwise of the end of the shelf, and means for permitting sliding adjustment of said plate on said shelf and the clamping of said plate to said shelf in adjusted position, said supporting means for the said shelf having a projection received by said slot, the said shelf being positioned forward or back in said case-section by contact of the end walls of said slot with said projection, substantially as and for the purpose described.

29. In an extensible case, the combination with a case-section having sides and a door hinged thereto on upright axis, a shelf, door-securing means on said shelf, co-acting means therefor extending up and down on said door, means for positioning said shelf at various elevations between the sides, a plate secured to the shelf at each end thereof, engaging means between said plate and said supporting means, and adjusting means for permitting sliding of said plate on said shelf and locking of said plate thereon in adjusted position for moving therewith, and thereby permitting adjustment of relative position between said shelf and said supporting means for positioning the shelf with relation to the front of the case-section for causing proper connection between said door-securing means and co-acting means, substantially for the purpose specified.

30. In an extensible case, the combination of units arranged to be superposed for forming a case, immediately superposed units having dowel and dowel hole connection between the same located solely adjacent to the front edges therefor with sidewise shiftable connection throughout the balance of said meeting ends.

31. In an extensible case, the combination of open-ended case-sections, each comprising a pair of sides arranged to be superposed,

connecting means embedded in said sides between superposed sides and comprising a pivoted lever secured to one side arranged to swing on its pivot and span the superposed ends of said superposed sides, and engaging means arranged eccentrically with relation to the pivot of said lever on the other side, constructed and arranged for drawing one superposed side closer toward the other upon successive engagement of said lever with said eccentrically arranged engaging faces.

32. In an extensible case, the combination of open-ended case-sections, each comprising a pair of sides arranged to be superposed, and connecting means between superposed sides comprising a pivoted lever secured to one side arranged to swing on its pivot and span the superposed ends of said superposed sides, and a resilient lug on the other side, said lever taking between said lug and side and being yieldingly pressed by said lug, and constructed and arranged for drawing one superposed side toward the other.

33. In an extensible case, the combination of open-ended case-sections, each comprising a pair of sides arranged to be superposed, connecting means embedded in said sides between superposed sides and comprising a pivoted lever secured to one side arranged to swing on its pivot and span the superposed ends of said superposed sides, engaging means having stepped eccentric contact-face thereon on the other side for said lever, constructed and arranged for drawing one superposed side toward the other, and a stop on the side to which the lever is attached for limiting retraction of the lever.

34. In an extensible case, the combination of a case-section having sides, a base-section

and a top board therefor, said top board having rabbits at its sides for receiving the sides of a case-section, said top board also having a slot opening into said rabbit, a connecting lever for said case-section in said slot, and means embedded in the side of said case-section engaged by said lever.

35. In an extensible case, the combination of case-sections open-ended at top and bottom, door-sections therefor swinging in upright positions, said case-sections arranged to be selectively superposed and said door-sections respectively having an inner rabbit forming an inner end face and upright wall at one horizontal edge of the door and an outer end face and upright wall at the other horizontal edge thereof, and a clamp for spanning superposed door-sections and forcing the said outer end faces and outer ends of said walls vertically toward each other for uniting said door-sections into a united door, the said upright walls lapping each other with side pressure for forming close connection between said door-sections, substantially as described.

36. In an extensible case, the combination of case-sections each having sides and door-sections, the tops and bottoms of said door-sections respectively having extensions respectively at the inside and outside edges of said respective door-sections, and clamping means between said door-sections.

In witness whereof I have signed my name hereto in the presence of two subscribing witnesses.

EDWARD G. SCHRIEFER.

Witnesses:

ERNEST G. SIMON,
HERBERT F. HARDEN.

It is hereby certified that in Letters Patent No. 909,951, granted January 19, 1909, upon the application of Edward G. Schriefer, of Cincinnati, Ohio, for an improvement in "Extensible Cases," an error appears in the printed specification requiring correction, as follows: In line 123, page 8, the word "therefor" should read *thereof*; and that the said Letters Patent should be read with this correction therein that the same may conform to the record of the case in the Patent Office.

Signed and sealed this 23rd day of February, A. D., 1909.

[SEAL.]

C. C. BILLINGS,
Acting Commissioner of Patents.
